UNITED STATES PATENT OFFICE.

ORESTE G. AGNINI AND RALPH SINGER, OF CHICAGO, ILLINOIS.

SNAP BUCKLE.

Application filed February 23, 1928. Serial No. 256,092.

Our invention relates to snap buckles, and pertains more particularly to a two-piece buckle which is readily connected and disconnected, and which when connected gives the appearance of being formed of one piece. The invention is particularly adaptable for use in connection with buckles, the front or face plate portions of which are decorated or mounted with imitation gems such as are generally used on ladies' belts.

An object of the invention is to provide a two-piece buckle of simple construction without any movable parts, and of relatively small dimension in transverse section when assembled, so as to lie flat against the dress of the wearer.

A further object is the provision of a buckle of this type having means for conveniently engaging and disengaging the buckle parts so that the parts will remain in engaged position when worn with a loose belt, and which will simulate a solid or one piece face plate.

Other objects will appear hereinafter. The present application represents an improvement upon the invention covered by applicants' co-pending application, Serial No. 253,540, filed February 11, 1928, and the invention will be best understood by reference to the accompanying drawings forming a part of this specification, and in which,

Figure 1 is a front view of an assembled buckle showing a portion of the belt fabric at either side; Figure 2 is a view of the back of the assembled buckle shown in Figure 1; Figure 3 is a view of the back of the outer or frame member; Figure 4 is a view of the back of the inner member, both of the forms shown in Figure 1; and Figure 5 is a horizontal sectional view taken on the line 5—5 of Figure 2.

Figure 6 is a front view of an assembled buckle in a modified form; Figure 7 is a view of the back of the assembled buckle shown in Figure 6; Figure 8 is a view of the back of the outer or frame member; Figure 9 is a view of the back of the inner member, both used in the form shown in Figure 6; and Figure 10 is a horizontal sectional view taken on the line 10—10 of Figure 7.

Referring to the form shown in Figures 1 to 5 inclusive, an outer or frame member 12 is provided with a loop 13 for attaching one end of a belt, the inner ends 14 of the wire forming the loop 13 projecting inwardly of the frame 12, for the purpose of retaining

an inner member in place in assembling. Disposed at the inner edge of the frame 12, opposite the edge having the projections 14, are flanged portions 15. The inner member 16 (Fig. 4) is also provided with a loop extension 17 to which is secured the other end of the belt, and is further provided with a spherical lug 18, secured to the plate 16 by a shank of reduced diameter. In assembling this form, it is but necessary to insert the inner member 16 in a diagonal direction through the central opening of the outer or frame member 12 after which the back of member 16 bears against the flanged projections 15 on the frame 12. Also in assembling, the spherical projection 18 spreads the wire projections 14, which spring back into place on either side of the shank of the projection 18 to securely hold the two buckle parts together as shown in Figures 2 and 5.

The slightly modified form shown in Figure 6 to Figure 10 inclusive, operates upon the same principle as the form shown in Figure 1 to Figure 4 inclusive, and like reference numerals will indicate like parts in the respective views. In the form shown in Figure 6 to Figure 10 inclusive, the spherical projection 18 is mounted upon the frame member 12, and the wire forming the loop 17 is extended as at 19 (Fig. 9) to form a projection adapted to be inserted in socket 20 provided on the frame 12. Further, the flanged portions 15 are provided on the inner member 16. In assembling this form, the projection 19 is inserted in the socket 20, and the wire forming the loop 17 makes spring engagement with the spherical projection 18, as shown in Figures 7 and 10.

The thin cross-sectional dimension of the assembled buckle causes it to lie flat against the garment of the wearer. The assembled buckle has the appearance of being constructed of one piece, and the securing means enables the buckle to be worn upon a loose belt or sash, as well as providing an efficient and reliable buckle when the belt is tightly worn. Except for the slight spring action of the wire loop in connecting the parts together, the buckle is devoid of any movable parts, which would increase the size of the buckle, and render it more inconvenient to the user.

While we have illustrated and described the preferred forms of construction for carrying our invention into effect, this is capable of variation and modification with-

out departing from the spirit of the invention. We, therefore, do not wish to be limited to the precise details of construction set forth, but desire to avail ourselves of such 5 variations and modifications as come within the scope of the appended claims.

Having described our invention, what we claim as new and desire to secure by Letters Patent is:

- 10 1. A buckle of the class described comprising, in combination, a frame member and an inner member, said frame member having an opening adapted to receive said inner member, said inner member adapted to be inserted and retained in the opening in said frame member, a flanged projection extending between said members, and a projection upon one of said members adapted to be engaged by a spring portion on the other member for securing said members together upon assembling.
- 15 2. A buckle of the class described comprising, in combination, a frame member and an inner member, said frame member having an opening adapted to receive said inner member, said inner member adapted to be
- 20
- 25

inserted and retained in the opening in said frame member, a flanged projection extending between said members, and a spherical lug mounted upon one of said members and adapted to be engaged by resilient means mounted upon the other member for securing said members together upon assembling. 30

3. A buckle of the class described comprising, in combination, a frame member and an inner member, said frame member having an opening adapted to receive said inner member, said inner member adapted to be inserted and retained in the opening in said frame member, a flanged projection extending between said members, and a spherical lug mounted upon one of said members and connected thereto by a shank of reduced diameter, said lug adapted to be engaged by resilient means mounted upon the other member for securing said members together upon 35 40 45 assembling.

In testimony whereof we have signed our names to this specification.

ORESTE G. AGNINI.
RALPH SINGER.
